UNITED STATES PATENT OFFICE.

GORDON R. McDONALD, OF SCHENECTADY, NEW YORK, ASSIGNOR TO GENERAL ELECTRIC COMPANY, A CORPORATION OF NEW YORK.

PROTECTIVE DEVICE.

Application filed May 28, 1925, Serial No. 33,584. Renewed September 5, 1928.

My invention relates to improvements in protective devices and has for an object to provide an improved protective device which operates in response to the rate of increase 5 of current at some predetermined value of current when the current increases slowly and at a lower value of current when the current increases rapidly.

My invention will be better understood 10 from the following description taken in connection with the accompanying drawings, and its scope will be pointed out in the appended claims.

In the accompanying drawings, Fig. 1 15 illustrates an embodiment of my invention in a circuit breaker, and Figs. 2 and 3 illustrate the embodiment of my invention shown in Fig. 1 in elevation and perspective respectively, certain parts being shown cut 20 away in Fig. 3.

Fig. 1 shows a circuit breaker mounted on a switchboard 1 and comprising a movable circuit controlling element such as a brush 2, which is arranged to bridge terminal studs 25 3 and 4. The circuit breaker also comprises secondary contacts 5 and 6 which may be suitably disposed in an arc chute 7 provided with a blowout coil 8. The brush 2 is mounted on an arm 9 pivoted at 10 and is 30 arranged to be moved to the circuit closed position by a solenoid comprising a plunger 11 and to be held in the circuit closed position by a restrained underset toggle comprising links 12 and 13. The toggle is 35 restrained by a latching mechanism comprising a main latch 14 arranged to engage the link 13 at 15 and an auxiliary latch 16 arranged to engage the main latch 14 at 17, the latches being biased to latching position 40 by a spring 18.

In Fig. 1, the circuit breaker is shown in the circuit closed position, the brush 2 being held against the bias of gravity and the brush pressure by the toggle and latching 45 mechanism. To trip the circuit breaker, that is, to release the brush 2 for movement to the circuit open position, the auxiliary latch 16 is moved counterclockwise about its pivot 10. This releases the main latch 14, 50 which then slips off the link 13 and permits the toggles 12, 13 to buckle. The arm 9 is then free to turn clockwise.

For tripping the circuit breaker, that is, 55 releasing the latch 16 in response to abnormal circuit conditions, I provide means, in-

dicated generally as 19, which is operative in response to the rate of increase of a continuous current at some predetermined value of current when the current increases slowly and at a lower value of current when the 60 current increases rapidly. This means, shown more in detail in Figs. 2 and 3, comprises an energizing winding which in the case of a direct current circuit breaker may be the terminal stud 4 as shown, an armature 65 20 having a portion 21 which is arranged on movement of the armature in one direction, counter-clockwise as seen in Fig. 2 to engage the latch 16 whereby to release the latching mechanism, and a magnetizable member 22 70 comprising two branches or main and shunt or parallel flux paths 23 and 24 for the flux through the armature. These paths present spaced poles 25, 26 of like polarity on opposite sides of the armature. The magnetizable member 22 may be U-shaped to straddle the stud 4 and may be supported by being secured thereto by a suitable fastening means such as a screw 27. The shunt flux path comprises the magnetizable elements 75 24, 26, 28 and 29. The pole piece or member 26 may be adjustably positioned in the member 29 so as to provide for changing the gap between the armature 20 and the pole 25.

Normally the distribution of the flux of 80 the magnetizable member 22 in the main and shunt flux paths is such that the armature 20 is maintained against the pole 26 of the shunt flux path, the restraining effect being increased by the bias of gravity and 85 suitable adjusting means such as a spring 30, the tension of which is arranged to be varied by a screw 31 mounted in a suitable supporting member 32. In order that the armature 20 may be attracted to the pole 90 25 on the occurrence of a slowly increasing continuous current in the winding or stud 4, the shunt flux path 24 is arranged to saturate at some predetermined current such that the pull between the armature 20 and the pole 25 exceeds the pull between the armature 20 and the pole 26, the bias of 95 gravity and the tension of the spring 30. When this occurs, the portion 21 of the armature 20 moves downward and turns the latch 16 counterclockwise to trip the circuit breaker. Thus in the case of overloads, that is, slowly increasing current, the attractive effort of the shunt flux path increases up to 100 a certain point, that is, the current necessary 105 110

- to saturate the shunt flux path. This attractive effort then becomes substantially constant, and further increase in the current increases the pull between the armature 20 and the pole 25 until the armature, at some predetermined value of current dependent on the setting of the spring 30 and the spacing of the poles 25 and 26, is moved to release the latch 16.
- 10 In the case of short circuits, the current increases very rapidly, and it is desirable to effect the tripping of the breaker during the rising period of the current and before it has reached a high value. For this purpose, I provide means such as a closed circuit winding or copper cylinder 33 on the shunt flux path for effecting such a change in the distribution of the flux in the main and shunt paths, that the armature 20 will 15 be attracted to the pole 25 at a lower value of current than is the case when the current increases slowly. In this case, since the current is rapidly increasing, the shunt flux path does not saturate because the 20 closed circuit winding 33 delays or chokes back the flux in the member 24 so that substantially all the flux is turned back or diverted into the main flux path 23 and the restraint or pull of the shunt flux path is 25 substantially nullified.
- 30 While I have shown and described only one embodiment of my invention, I do not desire to be limited to the exact arrangement shown but seek to cover in the appended claims all those modifications that fall within the spirit and scope of my invention.

What I claim as new and desire to secure by Letters Patent of the United States, is:—

1. In combination with a circuit breaker 40 and a latching mechanism for holding the circuit breaker closed, means for releasing the latching mechanism on the occurrence of abnormal circuit conditions comprising, an armature having a portion arranged on 45 movement of the armature in one direction to engage the latching mechanism whereby to release the same, an energizing winding, a magnetizable member comprising two branches arranged to form parallel magnetic 50 paths for the flux through the armature, one of said branches being arranged magnetically to saturate on the occurrence of a slowly increasing continuous current in said winding whereby to effect movement of the armature in said direction when the current has 55 reached a predetermined value, and means for effecting movement of the armature in said direction on the occurrence of a rapidly increasing continuous current in said winding before the current reaches said predetermined value comprising a closed circuit winding on the branch arranged to 60 saturate for controlling the distribution of the flux of said member in the branches 65 thereof.

2. In combination with a circuit breaker and a latching mechanism for holding the circuit breaker closed, means for releasing the latching mechanism on the occurrence of abnormal circuit conditions comprising, a 70 magnetizable member having main and shunt flux paths presenting two spaced poles, an energizing winding for said member, and an armature having one end movable between said poles, the normal distribution of 75 the flux of said member in said paths with a continuous current in said winding being such as to maintain said end of the armature against the pole of the shunt flux path characterized by the fact that the shunt path is arranged to saturate on a predetermined value of continuous current in said winding to effect the movement of the armature to the pole of the main path when a continuous current increases slowly in said winding to 80 a value exceeding said predetermined value whereby to release the latching mechanism and by the fact that the shunt path is provided with a closed circuit winding to effect a change in the distribution of the flux of 85 said member in said paths on a rapidly increasing continuous current whereby to effect the movement of the armature to the pole of the main path on a rapidly increasing current before the current reaches said 90 predetermined value to release the latching mechanism.

3. In a circuit interrupting device where in a movable circuit controlling element is provided with a latching mechanism for 100 holding the element in circuit closing position, means for effecting the release of the latching mechanism on the occurrence of abnormal circuit conditions comprising an energizing winding, a magnetizable member 105 having two branches arranged to present spaced poles of like polarity, one of said branches having a limited flux capacity so as to saturate on a slowly rising continuous current in said winding when the current reaches a predetermined value, an armature having one end movable between said poles, said armature being arranged normally to be held against the pole of the branch of limited flux capacity and to be attracted to 110 the other pole when a slowly rising continuous current in said winding exceeds said predetermined value whereby to effect the release of said latching mechanism, and means for causing the armature to be attracted to said other pole on the occurrence of a rapidly increasing continuous current in said winding before the current reaches said predetermined value whereby to effect the release of said latching mechanism comprising a closed circuit winding on the branch of limited flux capacity for controlling the distribution of the flux of said member in the branches thereof.

4. In a direct current circuit breaker 130

- wherein a movable circuit controlling element is provided with a latching mechanism for holding the element in circuit closing position, means for effecting the release of
- 5 said latching mechanism on the occurrence of abnormal current conditions comprising an energizing winding adapted to be connected in series relation with the circuit, a magnetizable member having two branches
- 10 arranged to present spaced poles of like polarity, one of said branches having a limited flux capacity so as to saturate on a slowly rising current when the current reaches a predetermined value, a pivoted armature
- 15 having one end movable between said poles, said end of the armature being arranged normally to be held against the pole of the branch of limited flux capacity and to be attracted to the other pole on the occurrence
- 20 of a slowly rising current exceeding said predetermined value whereby to effect the release of said latching mechanism and means for causing the armature to be attracted to said other pole on the occurrence of a rap-
- 25 idly rising current before the current reaches said predetermined value whereby to effect the release of said latching mechanism comprising a closed circuit winding on the branch of limited flux capacity for control-
- 30 ling the distribution of the flux of said member in the branches thereof.
5. In a device of the class described, a magnetizable member having main and shunt flux paths presenting two spaced poles, an energizing winding for said member, an armature having one end movable between said poles, means for biasing said end of the armature to the pole of the shunt path, said member being constructed so that the distribution of the flux in said paths with a continuous current in said winding below a predetermined value is such as to assist the biasing means to hold the end of the armature against the pole of the shunt path, said shunt path being arranged to saturate with a continuous current in said winding above said predetermined value to effect the movement of the end of the armature to the pole of the main path when a continuous current increases slowly in said winding, and a closed circuit winding associated with said shunt path for effecting a change in the distribution of the fluxes in said paths on a rapidly increasing continuous current in said winding whereby to effect the movement of the end of the armature from the pole of the shunt flux path to the pole of the main flux path at a lower value of the current than when the current is increasing slowly.

In witness whereof, I have hereunto set my hand this 26th day of May, 1925.

GORDON R. McDONALD.
